UNITED STATES PATENT OFFICE

145,980

DESIGN FOR A BOTTLE CLOSURE

Leo M. Mallick, Chicago, Ill.

Application December 29, 1945, Serial No. 125,149

Term of patent 7 years

(Cl. D58—10)

To all whom it may concern:

Be it known that I, Leo M. Mallick, a citizen of the United States, residing at Chicago, county of Cook and State of Illinois, have invented a new, original, and ornamental Design for a Bottle Closure, of which the following is a specification, reference being had to the accompanying drawing, forming a part thereof, in which:

I claim:

The ornamental design for a bottle closure, as shown.

LEO M. MALICK.
